(57) **CLAIM**

The ornamental design for a computer assembly housing, as shown and described.

DESCRIPTION

FIG. 1 is a front top perspective view of a first embodiment of a computer assembly housing;

FIG. 2 is a front view of the design of FIG. 1;

FIG. 3 is a rear view of the design of FIG. 1;

FIG. 4 is a right side view of the design of FIG. 1;

FIG. 5 is a left side view of the design of FIG. 1;

FIG. 6 is a top view of the design of FIG. 1;

FIG. 7 is a bottom view of the design of FIG. 1;

FIG. 8 is a front top perspective view of a second embodiment of a computer assembly housing;

FIG. 9 is a front view of the design of FIG. 8;

FIG. 10 is a rear view of the design of FIG. 8;

FIG. 11 is a right side view of the design of FIG. 8;

FIG. 12 is a left side view of the design of FIG. 8;

FIG. 13 is a top view of the design of FIG. 8; and,

FIG. 14 is a bottom view of the design of FIG. 8.

The even-dashed broken lines shown in the figures represent boundaries of the claim. The even-dashed broken lines and any unshaded surfaces within the boundary lines form no part of the claimed design.
